UNITED STATES PATENT OFFICE.

HAMILTON A. JUKES, OF WINNIPEG, MANITOBA, CANADA.

CAR-COUPING.

SPECIFICATION forming part of Letters Patent No. 355,174, dated December 28, 1886.

Application filed May 8, 1886. Serial No. 201,613. (No model.)

To all whom it may concern:

Be it known that I, HAMILTON AUGUSTUS JUKES, of the city of Winnipeg, in the county of Selkirk and Province of Manitoba, Canada, 5 a British subject, have invented certain new and useful Improvements in Car-Couplers, of which the following is a specification.

My invention relates to improvements in car-couplers in which the operation of coupling is greatly facilitated and the time occupied in so doing reduced to a minimum, besides which the danger to the brakeman of going between the cars is avoided altogether. I attain these objects by the mechanism illus- 15 trated in the accompanying drawing, which is part longitudinal section, part side elevation, of draw-head embodying my invention.

D is the draw-head, externally somewhat similar to those now in use, but is cast with a 20 deep bell-mouth, as shown, and a chamber of the peculiar shape shown on the drawing, the lower portion rounded for the reception of the link-bar C, as shown, having its sides parallel, of the shape shown in section, and slotted to 25 receive the key A.

B is a claw working on a pin, and rises in the cavity when the link or flattened pin is introduced, and returns to its position of its own weight before the key A is pushed forward.

30 C is a flat bar with ends rounded and enlarged, as shown, and slotted, so that it may be

used with pin when it is desired to connect with one of the draw-heads now in use.

A is the key, which is worked by a lever suitably placed and extending to the side of 35 the car. In the action of coupling, the bar C is pushed into the cavity. The draw-heads then touch, and the pressure is continued until the key A is stopped by the plate E, attached to the bottom of the car. The key A is then 40 pushed forward, while the draw-head recedes under pressure against the spring, the result being that the motion locks the cars together completely.

To unlock, all that is necessary is to move 15 the lever acting on the key A, and the cavity formed admits space enough for the claw B to rise sufficiently to let the bar C out, when it is ready, without any further adjustment, to be coupled again.

What I claim as my invention, and what I 50 desire to patent, is—

The peculiar form of the cavity in draw- 55 head D, in combination with the claw B, working on the pin, the key A, operated by the lever, the plate E, attached to the bottom of the car, and the bar C, slotted or plain, substantially as and for the purposes above set forth.

H. A. JUKES.
